RETURN BEND FOR CRACKING STILLS

Herbert C. Stockham, Birmingham, Ala., assignor
to Fred C. Fantz, Webster Groves, Mo.

Application March 14, 1932, Serial No. 598,648

3 Claims. (Cl. 285—20)

My invention relates to that class of return bends which are used in refinery apparatus, such as oil cracking stills, where the tubes are located in nests or banks and must be provided with connections on their ends so as to ensure an uninterrupted flow of the liquid from one tube to its next adjacent tube and to provide an uninterrupted surface.

It is well known that the high pressure and temperature sometimes causes these tubes to warp so that it is essential to provide some means to hold the tubes in position, when the return bend has been removed for the purpose of cleaning the tube of the coke which deposits rapidly on their interior when the still is in operation, also for the purpose of permitting inspection of the tubes or the removal of a damaged tube. This is best accomplished by making a unitary housing in which the return bend is mounted.

In a device of this character it is essential that means be provided for the convenient removal of the return bend and also convenient replacement of the tubes.

My invention is designed as an improvement upon the device shown in Patent No. 1,831,709.

My invention has for its object to provide an improved joint. As shown in the patent referred to, the joint is formed on the collar or bushing which is screwed on to the end of the still tube.

My invention is designed to provide for the joint on the end of the tube itself so that the pressure exerted to tighten the joint will be entirely for compression.

A further object is to avoid the necessity of having to roll the tube into the threads to render them gas tight.

My means of accomplishing the foregoing objects may be more readily understood by having reference to the accompanying drawing which is hereto annexed and made a part hereof, in which—

Fig. 1 is a side elevation, one-half of the housing being broken away and the part shown in section, fragmentary portions only of the tube being shown as my invention is only concerned with the ends of the tubes;

Fig. 2 is a vertical section through one of the tubes housing and return bend; and

Fig. 3 is a top or plan view, one-half of the return bend being broken away and the securing means being omitted so as to show the interior construction of the housing.

Similar reference numerals refer to similar parts throughout the entire description.

As shown in the drawing my invention com-

prises a return bend 1 which is designed to connect still tubes 2 and 3. As the joint between the tubes 2 and 3 and the face of the return bend are identical I shall only describe a single joint and its component parts.

The return bend 1 is mounted in a housing 4 which consists of two annular members 5 and 6. These members are connected by a web or webs 7. Each of the members 5 and 6 are provided with upwardly extending arcuate side walls 8 and 9, the exterior which is preferably polygonal to facilitate closer nesting of the tubes.

The walls 8 and 9 are provided with slots 10 and 11 adjacent their upper ends in which are mounted plates 12. Each of the plates 12 carries a set screw 13, the inner end of which bears against an abutment 14, cast or formed, on the exterior wall of the return bend 1. Each face 15 of the return bend 1 is provided with an annular V shaped groove 16 which is fitted to an upwardly projecting annular ridge 17 which is convex in cross section and is adapted to fit the grooves 16 forming a line contact. This ridge projects from the end of the still tubes.

The ends of the tubes 2 and 3 are provided with threads 18 upon which is screwed a collar 19 which is provided with external shoulders 20 adapted to interlock with shoulders 21 formed on the internal surface of the openings in the annular members 5 and 6 of the housing.

It will be apparent to persons skilled in the art that the collar 19 is screwed on the tube only for the purpose of keeping it from pulling out from the annular members 5 and 6.

The device is assembled as follows: The housing is first slipped over the tubes 2 and 3, the tubes passing through the openings in the annular members when the collars 19 are screwed on to the threads 18—this may be done in any convenient or suitable manner by socket wrench or spanner for example.

The return bend 1 is then placed in the housing, the grooves 16 in the faces of the return bend engaging the annular ridges 17 on the ends of the tubes. The plates 12 are then placed in position and the set screws 13 tightened up. This serves to draw the tubes into tight engagement with the return bend.

It will be apparent from the foregoing description that the collar 19, fitting as it does into the annular members, serves to hold the tubes 2 and 3 in spaced relation to each other so that it is impossible for them to spring apart when the return bend is removed for the purpose of cleaning etc. Although I have shown the col-

lars 19 as circular it is apparent that they could, if desired, be formed square or hexagonal, where, in the location in which they are to be used, such construction might permit of closer nesting than would be the case where they are circular. Obviously the threads may be Briggs standard, A. P. I., or any special form which may be desired.

It will be apparent from the foregoing description that I have provided a form in which the pressure and temperatures are resisted by the compression of the return bend upon the end of the tube rather than upon the end of the collar. This tends to ensure the maintenance of a leak-proof joint which is highly essential in devices of this character. For the purpose of complete disclosure of a concrete device, I have described with some degree of particularity a type of joint but it is obvious that any desired type may be employed.

Having described my invention what I regard as new and desire to secure by Letters Patent is:

1. In a high pressure refinery apparatus, a conventional return bend adapted to connect a pair of adjacent still tubes, to provide a continuous passageway therethrough, a hexagonal shouldered collar continuous in cross section secured adjacent the ends of each tube, the end of the tube projecting through said collar, a housing member comprising annular portions having hexagonal openings therethrough, the walls of which are adapted to abut the shoulders

on the collar and means carried by the housing to draw the face of the bend and the ends of the tubes into a leak-proof joint.

2. In a high pressure refinery apparatus, a conventional return bend adapted to connect a pair of adjacent still tubes, to provide a continuous passageway therethrough, a polygonal shouldered collar continuous in cross section secured adjacent the ends of each tube, the end of the tube projecting through said collar, a housing member comprising annular portions having polygonal openings therethrough, the walls of which are adapted to abut the shoulders on the collar and means carried by the housing to draw the face of the bend and the ends of the tubes into a leak-proof joint.

3. In a high pressure refinery apparatus, a conventional return bend adapted to connect a pair of adjacent still tubes, to provide a continuous passageway therethrough, a hexagonal shouldered collar continuous in cross section secured adjacent the ends of each tube, the end of the tube projecting through said collar, a housing member comprising annular portions having hexagonal openings therethrough, the walls of which are adapted to abut the shoulders on the collar and means carried by the housing to draw the face of the bend and the ends of the tubes into a leak-proof joint, the outer walls of which are hexagonal in cross section whereby closer nesting of the tubes is attained.

HERBERT C. STOCKHAM.
